[57] CLAIM

The ornamental design for game board or similar article, as shown and described.

DESCRIPTION

FIG. 1 is a top plan view of a game board or similar article, showing our new design;

FIG. 2 is a front elevational view of the article of FIG. 1, the rear and side views being substantially identical thereof; and

FIG. 3 is a cross-sectional view of the article of FIG. 1 taken generally along line 3—3 thereof.

FIG. 3

FIG. 2
